UNITED STATES PATENT OFFICE.

JOHN BRICKEN, OF CHICAGO, ILLINOIS.

PENCIL.

Application filed September 22, 1920. Serial No. 412,880.

To all whom it may concern:

Be it known that I, JOHN BRICKEN, a citizen of United States, residing at Chicago, in the county of Cook and State of Illinois, have invented certain new and useful Improvements in Pencils, of which the following is a specification.

This invention relates to improvements in pencils.

10 The principal object of the invention is to provide a pencil consisting of two coacting barrel members and a cap member, by which the relative adjustment of said barrel members may be conveniently effected. An-
15 other object is to provide a pencil of simple construction, and one which is adapted to be rapidly and inexpensively manufactured.

Other objects relate to features of construction and arrangement which will appear more fully hereinafter.

In the drawing—

Figure 1 is a section taken on a vertical plane longitudinally through the pencil;
25 Fig. 2 is a broken view showing the construction of a modified form of the pencil; and

Fig. 3 is a view similar to Fig. 1, showing a further modification of the pencil.

30 The same reference characters are used to indicate similar elements in the two views, in which—

1 is an outer barrel of sheet metal having a tapered end 2 and an opening formed 35 therein to receive and hold a lead 3, of proper size. 4 is an inner barrel, of similar material, adapted to be moved within said outer barrel to adjust the lead as desired, the end of the inner barrel being tapered 40 and blunt, and against which the end of the lead abuts. A cap member 5, preferably of rubber, and similar to the form shown, is secured to the outer end of the inner barrel, and affords a convenient grip for adjust-
45 ing the inner barrel longitudinally, to cause the lead to protrude farther from said outer barrel as it is worn in use. This cap member extends toward the point of the pencil sufficiently to normally enclose the upper 50 end of said outer barrel, and, if made of soft rubber, affords a convenient eraser. It may, if desired, be made of hard rubber, metal, or composition material.

Referring particularly to Fig. 1, it will 55 be seen that the inner barrel 4 has threads

6 formed adjacent the outer end thereof, which coact with corresponding threads formed in the reduced portion 5^a of the recess 5^b of the cap member 5, by which said cap member is removably attached to 60 said inner barrel.

In the sides of the inner barrel I provide one or more slots 7, around which the metal is slightly expanded, to afford sufficient frictional contact with the outer barrel to hold 65 said barrels in operative position against accidental relative movement, but at the same time affording such contact as will permit the user of the pencil to slide said inner barrel longitudinally within said outer barrel to adjust the lead 3, as required. The inner barrel may be used as a magazine for extra leads, the slots 7 being of insufficient width to permit the leads to drop through.

In using the pencil illustrated in Fig. 1 the operator unscrews the cap 5 from the inner barrel, removes a lead therefrom, and inserts it in the opening 1^a of the outer barrel, which frictionally retains the same 70 against unintentional removal. The cap is then replaced and the barrels adjusted longitudinally to accommodate the inserted lead, as will be clear.

In the form of pencil shown in Fig. 2 75 the cap 5 may be made of metal, having the threaded recess 5^b adapted to coact with the threaded portion of the outer barrel 1. The end of the inner barrel 4 fits in the reduced recess 5^a of the cap 5, and is held therein 80 by means of lugs 8 struck up from said inner barrel into cavities 9 of the cap member, or by other means.

One or more longitudinal slots 11 are formed in the threaded portion of the outer 85 barrel, by means of which that portion of said barrel may be slightly expanded to ensure coaction between the threads thereof and the threads of the cap 5. Sufficient clearance between the barrels is provided to readily permit of relative longitudinal adjustment by the coaction of the threaded members. An opening 10 is provided in the inner barrel, of such size that extra leads may be inserted therethrough in using said 90 barrel as a magazine.

In the form shown in Fig. 3 the outer barrel has threads, preferably up-struck therefrom adjacent the upper end for a distance 95 slightly greater than the length of the lead 100

to be used with the pencil. Corresponding threads are formed in the recess 5^b of the cap member 5, which coact with the threads of the outer barrel. The cap member is secured 5 to the inner barrel by means of lugs 8, preferably up-struck from said inner barrel, the lugs entering small cavities 9 formed in the cap member, as shown.

A longitudinal slot 10 is provided in the 10 inner barrel, of sufficient size to permit the insertion and removal of leads, whereby the barrel may be used as a magazine for extra leads.

By turning the cap 5 the coaction of the 15 threads thereof with the threads of the outer barrel will cause the cap member to travel toward the point of the pencil, thus moving the inner barrel longitudinally within said outer barrel to adjust the lead as desired, 20 there being only slight friction between said barrel members, which readily permit such relative movement.

Although I have shown and described three forms of my invention, it is obvious 25 that various other modifications and improvements may be made therein without departing from the scope of the invention, as defined in the appended claims.

I claim:—

- 30 1. A pencil comprising an outer tubular member, an inner tubular member, and a cap coacting with and enclosing the upper ends of both said members, said inner member having an opening therein whereby said 35 member may be used as a magazine for leads, said opening being closed by said

outer member when said inner and outer members are in assembled relation.

2. In a device of the class described, an outer tubular member having a threaded 40 portion adjacent its upper end, an inner tubular member having a plurality of lugs adjacent its upper end, a cap member, a threaded recess formed therein and adapted to coact with said threaded portion of said 45 outer member, and a reduced recess having cavities therein adapted to engage said lugs formed in said inner member.

3. A pencil having an outer tubular member, an inner tubular member of slightly less 50 diameter than said outer member, and constituting a magazine for extra leads, a cap secured to the end of said inner member to advance the same, said cap also threadedly 55 engaging the adjacent end of said outer member to retain said members in assembled relation, and a lead projecting from the other end of said outer member and advanced by said inner member.

4. In a pencil an outer tubular member, 60 an inner member slidably therein, a threaded cap secured to the outer end of said inner member, and threads formed in said outer member and adapted to coact with the threads of said cap, the threads of one of 65 said members being slotted to provide resilient engagement thereof with the threads of said other member.

In testimony whereof, I have subscribed my name.

JOHN BRICKEN.
